UNITED STATES PATENT OFFICE.

RALPH L. MILLIKEN, OF STANFORD UNIVERSITY, CALIFORNIA.

CLASP FOR OVERSHOES.

No. 897,476.

Specification of Letters Patent. Patented Sept. 1, 1908.

Application filed December 4, 1907. Serial No. 405,093.

To all whom it may concern:

Be it known that I, RALPH L. MILLIKEN, citizen of the United States, residing at Stanford University, in the county of Santa Clara and State of California, have invented certain new and useful Improvements in Clasps for Overshoes, of which the following is a specification.

The object of this invention is a simple, durable and efficient construction of clasp which is designed to be attached to articles, such as coats and the like, when they are left in cloak-rooms or are checked, and which forms a means of ready identification for such articles. And a further object of the invention is an improved device of this character which may be conveniently applied to small articles as overshoes, hats or the like, to fasten them together and which may be readily removed therefrom.

With this and other objects in view as will more fully appear as the description proceeds, the invention consists in certain constructions and arrangements of parts that I shall hereinafter fully describe and claim.

For a full understanding of the invention and the merits thereof, reference is to be had to the following description and accompanying drawing, in which:

Figure 1 is a perspective view of my improved clasp showing it applied. Fig. 2 is a view in elevation thereof. Fig. 3 is a detail perspective view, and Fig. 4 is a view in elevation showing the rocked position of the jaws.

Corresponding and like parts are referred to in the following description and indicated in all the views of the drawing by the same reference characters.

My improved clasp is preferably constructed of an integral strip of spring material doubled upon itself intermediate of its ends to form the spaced arms 1, the ends of which are bent outwardly as indicated at 2. The extremities of the strip are then doubled inwardly upon themselves to form the converging spring jaws 3, which are crimped inwardly at opposite intermediate points as indicated at 4. The inner extremities of the jaws 3 are normally in contact and are each serrated to form a series of engaging teeth 5.

A name, initials, or any suitable identify-

ing inscription or design is stamped, etched, painted or provided in any convenient manner on the outer side of one or both of the arms 1, as indicated at 6.

In the practical use of my improved clasp, it is slipped over a portion of the article or articles to which it is to be applied as illustrated in Fig. 1, so that said portion is passed between the converging spring jaws and is engaged by the teeth 5 of the inner ends thereof to be held securely therebetween, said article being readily identified by the inscription 6.

To remove the clasp from position the arms are pinched together near the ends 2 thereof. Such movement causes the crimped portions 4 to bear against the article and results in the jaws turning about the said crimped portions as fulcrums and in the rocking of said teeth out of engagement with the article so that the clasp may be readily drawn out of position.

From the above description in connection with the accompanying drawing, it will be seen that I have provided a clasp in which the engaging teeth may be held in spaced position during the application or removal of the clasp to or from an article, by pinching together the ends of the arms 1 and effecting a rocking movement of the jaws upon their crimped portions, in order to prevent any tearing or other like injury to said article.

Having thus described the invention, what I claim is:

The herein-described clasp consisting of a strip doubled upon itself to form spaced spring arms, the ends of the strip being returned inwardly with their extremities normally in engagement with each other and forming inwardly facing jaws, said jaws being normally spaced from each other except at such extremities and being crimped towards each other at corresponding points intermediate of their ends, as and for the purpose set forth.

In testimony whereof I affix my signature in presence of two witnesses.

RALPH L. MILLIKEN.
